UNITED STATES PATENT OFFICE

150,958

DESIGN FOR A MEAT SAW

Edward C. Karp, Belvidere, Ill.

Application August 5, 1946, Serial No. 132,292

Term of patent 14 years

(Cl. D55—1)

To all whom it may concern:

Be it known that I, Edward C. Karp, a citizen of the United States, residing at Belvidere, Boone County, Illinois, have invented a new, original, and ornamental Design for a Meat Saw, of which the following is a specification, reference being had to the accompanying drawing, forming a part thereof.

Figure 3 is a front elevational view of the saw as it appears in Figures 1 and 2; and

I claim:

The ornamental design for a meat saw, as shown.

EDWARD C. KARP.
